UNITED STATES PATENT OFFICE.

WILLIAM NICHOLAS, OF NEW YORK, N. Y., ASSIGNOR TO UNITED STATES GRAPHOTYPE COMPANY, A CORPORATION OF NEW YORK.

PROCESS FOR MAKING MATRIX-PLATES FOR MONOTYPE-MACHINES.

960,684.

Specification of Letters Patent. Patented June 7, 1910.

Application filed February 26, 1908. Serial No. 417,984.

To all whom it may concern:

Be it known that I, WILLIAM NICHOLAS, a subject of the King of Great Britain, residing at New York city, in the county and State of New York, have invented certain new and useful Improvements in Processes for Making Matrix-Plates for Monotype-Machines, of which the following is a specification.

10 My invention relates to a process for quickly and cheaply producing matrix plates for use in that class of type casting machines in which a complete layout or font of matrices is carried on a plate movable in 15 two directions in the machine, whereby any one of the matrices on the plate may be centered over a type body mold, so that by the combination of the type body mold and the matrix centered thereover, a type may be 20 cast. Such matrix plates may be made from any font of type to present any desired layout.

The object of the present invention is to make matrix plates of this character from 25 typefounder's type, so that any or all of the plates so made may register with, and be capable of interchangeable use in connection with a pin hole plate designed to be secured to the back of the matrix plate, and 30 to be used in coöperation with a centering pin for the purpose of truly centering each particular matrix over the mold.

Heretofore it has been found impossible 35 to make the matrix plate and the pin plate independently of each other when using typefounder's type. The practice heretofore pursued was first to make the matrix plate with the matrices thereon as evenly distributed as possible, then to attach there- 40 to a blank pin plate, place the two in a machine, move the attached plates to center one after another each matrix over a type corresponding thereto, and while so centered to bore in the pin plate by means of a 45 stationary drill the centering pin hole for each matrix. This process, however, is one of difficulty and uncertainty. It is a long operation, an inaccurate one, and one which never produced entirely satisfactory results, 50 because, owing to the method heretofore employed, of making the matrix plates, no two matrix plates could be identical in the spacing of their matrices, and consequently, no pin plate could be used with any matrix

plate except that one for which, as above 55 indicated, it was especially drilled.

My purpose is to produce pin plates in which the pin holes are drilled with mathematical accuracy at predetermined distances, and then to combine such plates with 60 matrix plates on which the matrices have also been spaced or positioned with mathematical accuracy, so that the independently made pin plates and matrix plates may be used interchangeably, and produced in 65 quantity independently of each other.

As a step preliminary to the process of the invention, the founder's type from which a matrix plate is to be produced is first milled off at the shoulder all around the 70 character so as to very considerably deepen or cut away the shoulder below the character. The font is then locked in a form with proper spacing in the lines, and with furniture between the lines, so as to locate the 75 characters about equi-distant apart. An electroplate is then made from the type thus set.

A type mold, which may conveniently be the mold of a type casting and composing 80 machine, is then set so that its aperture measures in one direction the distance between the aligned characters on the matrix plate, and in the other direction the distance 85 between the lines of characters on the matrix plate. The matrix plate is then attached to a pin plate having pin holes already drilled therein. It is sufficient if the pin holes approximately register with the matrices on the matrix plate. Thus attached, both plates 90 are placed in the machine. A cast is then made from the first matrix. The slug so cast is removed from the mold, and by the aid of a microscope and micrometer, the position of the character on the body is 95 measured.

It is intended that the characters shall each have a predetermined and tabulated relation to two sides of the slug body. If the examination of the slug discloses the fact 100 that the character does not occupy its correct position thereon, the variance is noted, and the position of the centering pin is slightly altered by suitable adjusting means, an amount such that upon another casting 105 the variance will be found to have been eliminated. The second or correct slug is accepted. This operation or series of opera-

tions is repeated for every matrix on the plate, until finally a complete and perfect set of type slugs is had. When this is accomplished, the slugs, equal in number to 5 the number of characters and quads upon the matrix plate are locked in a frame in the same order or arrangement as on the matrix plate first produced, and an electro-plate is then made therefrom. The matrix 10 plate so made has the matrices spaced thereon with mathematical accuracy at predetermined distances, and consequently may be used with any independently made pin plate in which the pin holes have been drilled at 15 the same mathematically computed distances. This same generic process may be carried into effect by a slightly different mode of procedure. Instead of assembling 20 in a form in the first instance all the founder's type to be copied, and proceeding as just indicated, each founder's type may be separately mounted in an adjustable form below a microscope, and the type adjusted in two directions until the type face occupies 25 its predetermined and tabulated position with respect to two sides of the form. An electroplate is then made of the type and form thus relatively positioned: a mold is then set to the size of the electroplate, and 30 a type slug cast.

The form in which the type is first adjusted is of such size that the mold when set to the electro taken therefrom will have an aperture measuring the mean distance 35 desired between the characters on the matrix plate to be made. The slugs thus made will necessarily, by reason of the first adjustment of the type in the form, have the characters correctly positioned thereon, so that the 40 second casting necessary in the first process is here unnecessary. When a complete set of type slugs for the entire font has thus been made, the slugs are assembled as in the first described procedure, and an electro- 45 plate taken upon which the matrices will be found to be spaced with mathematical accuracy, so that they may correspond accurately with pin holes independently drilled in a pin plate at the same mathematically 50 computed distances. The matrix plate produced by either of these processes may be used as a master matrix from which, by stereotype process, and electro process any 55 number of similar matrix plates may be made.

There are certain objections to the high shoulder of the founder's type. Unless this shoulder is cut down it will reappear in the matrices of the matrix plate, and then, if 60 by any chance or error, the shoulder in the matrix plate does not register and fit truly with the mold there will be formed a fin or offset on the type body when the latter is cast. These fins are objectionable in that 65 they prevent the type from lying properly

against each other in the galley line but give the assembled line of type what is known as a "fan" shape, that is to say, cause the lines of type to be longer at the top than at the bottom. When this occurs it 70 is impossible to lock the type properly in the form as the lines have a tendency to rise in the center. By reducing the shoulder in the type founder's type, the shoulder in the matrix is completely eliminated, and no 75 shoulder appearing in the matrix plate, the offsets or fins do not occur during the casting.

Having set forth the objects of the invention, I will now describe in detail one of the 80 means by which the invention may be carried into effect.

In the accompanying drawings: Figure 1 represents a standard piece of founder's type. Fig. 2 is a view of the same after 85 treatment thereof, in accordance with one of the steps of my process. Fig. 3 is a view illustrating the assembly of type characters, spaces and furniture in a frame, preliminary to obtaining the first electroplate, forming a 90 step of my process. Fig. 4 is a view showing in the frame an assembly of the slugs from which the electroplate forming the matrix or master matrix of my process is taken. Fig. 5 is a plan view of a matrix plate made 95 by my process. Fig. 6 is a cross-sectional view taken on the line 5-5 of Fig. 5. Fig. 7 is a pin plate on plan view.

The first few steps of the preferred manner of performing my process, are, 100 with the exception of the preliminary treatment of the founder's type, substantially identical with the first steps of the processes heretofore employed, that is to say: I assemble the various characters 1, 105 with proper spacing 2, and suitable type furniture 3, in a case 4, as illustrated in Fig. 3. Preliminary to such assembly, however, I first cut down in every instance shoulder 6 (see Fig. 1) of the type. This I do in a 110 milling machine in which the type is mounted, and the tool properly guided by means of a pantograph mechanism guided over the lines of an enlarged representation of the type obtained as by means of camera-lucida 115 process.

When the shoulders 6 have been cut down, the types are assembled in a frame as shown in Fig. 3. Whereas, heretofore, it has been necessary to obtain as nearly as possible a 120 precise spacing of the characters in the case 4, and to this end it has been necessary to carefully select the quads and furniture, in my process, however, no such careful spacing of the characters is necessary. An approximate spacing is entirely sufficient, and by eliminating the careful adjustment heretofore necessary at this stage of the process, much time and expense is avoided. The 125 characters being assembled as shown in Fig. 130

3, the next stage is to obtain the electroplate. This may be done in the usual manner. The electroplate having been obtained, it is provided with a pin plate the holes of 5 which are already drilled, and placed in position in the casting machine. It is immaterial in my process that the holes of the pin plate may not truly register with the character matrices in the matrix plate. It is not 10 expected that they will truly register; and an approximate registration is sufficient. It is in this respect that my process differs entirely from other processes, for instead of mounting a blank pin plate on the matrix 15 plate and proceeding to drill the pin holes therein to register with the matrices on the matrix plate, I use a drilled matrix plate, in the first instance as a means for producing individually a set of slugs 7, (see Fig. 4) of 20 a kind which I believe to be entirely unique. These slugs are preferably approximately square or rectangular in outline, and in number are equal to the number of characters and quads on the matrix block. In size the 25 slugs are exactly uniform, and they are of such a size that each is a factor or divisor of the distance in either direction across the face of the matrix block. Each slug has a character on its end face 8, except where the 30 slug is to be used in the production of a blank or space quad. Each character is so positioned on the slug with respect to two edges 9 and 10, thereof that when the slugs are properly assembled in the case 11, and 35 an electroplate 12, made from the assembly, the characters or matrices 13, on the electroplate will be absolutely correctly spaced with respect to each other, to the end that the electroplate thus made, may be used 40 with any pin plate in which the pin holes have been drilled at the same mathematically computed distances, and when so used may have the matrices thereon truly register with the holes in the pin plates.

45 It is impossible to obtain an electroplate directly from a block such as shown in Fig. 3 which can be used interchangeably with pin plates drilled at mathematically computed distances. If it were possible to se- 50 cure and maintain exactness in spacing in the assembling of type, quads and furniture, then the centering holes of the pin plate could be drilled at mathematically computed distances from one another, without refer- 55 ence to the matrix plate, so that, when pin plate and matrix plate were set together, each hole would necessarily register accurately with the character matrix opposite it on the matrix plate. The discrepancies be- 60 tween matrix plates, as heretofore made, are due apparently to a variety of causes. The larger number of pieces of type, and spacing, and type furniture, the small, and different bearing surfaces of types, the minute varia- 65 tion in set sizes of the type when faces are

selected from different type founder's type which consequently necessitates a different size of spaces for each matrix layout, and doubtless a number of other causes, contribute to give each block a different resiliency or compressibility when tightened in the case, and to make it impossible to set up and clamp two fonts of type, so that the electros produced therefrom are identical. Such obstacles of course do not present 70 themselves in the production of an electroplate from an assembly such as illustrated in Fig. 4.

In the assembly shown in Fig. 4 the number of slugs or pieces is small as compared 80 to the number shown in Fig. 3. Being few in number and of substantial size they present to each other a good bearing surface and do not have the elements of error present in the block shown in Fig. 3. I have 85 found that electroplates, though made from different fonts or sets of slugs 7, are for all purposes identical with each other and capable of interchangeable use with mathematically correct pin plates. To secure this 90 identity it is of course necessary that the characters be properly positioned on the slugs 7, but this last is a comparatively simple matter. The slugs with their characters are made in the following manner. 95 The mold is first set to the size of the slugs and is maintained in this setting while all the slugs are cast. The mold being properly set and the electroplate first made, having been set with a pin plate in position 100 in the machine, the operator commences the casting operation. The characters are cast one at a time of course as in the ordinary monotype machine. As soon as a slug with its character has been cast, it is, as 105 heretofore stated, examined under a microscope and with a micrometer to determine the position of the character on the slug with respect to the edges, 9 and 10, thereof. This position will generally be found to be 110 incorrect on the first casting. The operator then adjusts the pin or plunger of the machine an amount commensurate with the error shown by the measurement taken, and another and correct casting is made. In this 115 way, a slug is obtained in which the character will measure correctly to the predetermined and tabulated distances from each of the lines, 9 and 10, and such slug may be considered a perfect slug for this process. 120 One by one the different characters are presented to the mold, and the casting repeated until a correct slug for each character of a font is finally obtained.

When a correct set of slugs is obtained so 125 that each character will be in its true position on the block, the slugs are assembled in the case, as indicated in Fig. 4, or as in Fig. 4 except that the rows of slugs may be separated longitudinally by strips of metal 130

or furniture, and the character faces brought into true alinement by upsetting against a plane surface. Thereupon the case is clamped, the characters given the usual 5 graphite treatment, and an electroplate made therefrom. This last electroplate is capable of interchangeable use with all pin plates of a certain standard. Any quantity 10 of matrix plates can be reproduced therefrom. Matrix plates may, therefore, be supplied in quantity to the trade without the troublesome process of accompanying each with a specially drilled pin plate.

What I claim is:

15 1. A process for making matrix plates such as described, consisting in cutting from selected founders' type the shoulder at the base of the characters thereon, assembling such type in a case with means for approximately 20 spacing the type, making a matrix plate from the type so assembled, casting a set of slugs of uniform size, using in the casting operation the matrix plate obtained as above as a means for producing the 25 various character faces for the slugs so cast, repeating the casting after adjusting the position of the matrix plate with respect to the mold so that the slugs obtained will have the characters accurately positioned thereon, 30 assembling the uniform slugs thus obtained in proper position in a case and making a matrix therefrom as by means of an electrotyping process.

2. A process for making matrix plates 35 such as described, consisting in cutting from selected founders' type the shoulder at the base of the characters thereon, assembling such type in a case with means for approximately 40 spacing the type, making a matrix plate from the type so assembled, casting a set of slugs of uniform size, using in the casting operation the matrix plate obtained as above as a means for producing the various character faces for the slugs so cast, 45 repeating the casting after adjusting the position of the matrix plate with respect to the mold so that the slugs so obtained will have the characters accurately positioned thereon, assembling the uniform slugs thus obtained 50 in proper position in a case and making a matrix plate from the slugs so assembled.

3. A process for making matrix plates 55 such as described, consisting in assembling selected type in a case with means for approximately spacing the type, making a matrix plate from the type so assembled, casting a set of slugs of uniform size, using in the casting operation the matrix plate obtained 60 above as a means for producing the various character faces for the slugs so cast, repeating the casting after adjusting the position of the matrix plate with respect to the mold so that the slugs so obtained will

have the characters accurately positioned 65 thereon, assembling the uniform slugs thus obtained in proper position in a case and making a matrix plate from the slugs so assembled.

4. A process for making matrix plates 70 such as described, consisting in assembling selected type in a case with means for approximately spacing the type, making a matrix plate from the type so assembled, casting a set of type slugs, using in this 75 casting operation the matrix plate obtained as above as a means for producing the various character faces for the slugs so cast, repeating the casting after adjusting the position of the matrix plate with respect to 80 the mold so that the slugs so obtained will have the characters accurately positioned thereon, assembling the slugs thus obtained in proper position in a case and making a matrix plate from the slugs so assembled. 85

5. The process hereinbefore described, consisting in casting a layout of type slugs, each with a distinctive type character thereon, the several characters being differently positioned on the faces of their respective slugs 90 according to the measurements of the characters, and the slugs being of a size to be locked together without intervening spaces or space quads; arranging the slugs with respect to the unit of "set" measurement of 95 the characters thereon; and locking together the slugs so arranged to form the assembled layout.

6. The process hereinbefore described, consisting in casting a layout of type slugs of 100 uniform size, each with a distinctive type character thereon, the several characters being differently positioned on the faces of their respective slugs according to the measurements of the characters; arranging 105 and locking together said slugs to form the assembled layout.

7. A process of making matrix plates such as described, consisting in assembling selected type in a case with means for approximately 110 spacing the type, making a matrix plate from the type so assembled, then by means of a mold and said matrix plate casting a set of slugs with characters in precise and predetermined position thereon, the 115 slugs being of a size to be locked together without intervening spaces or space quads, then locking the slugs so assembled and making a master matrix plate therefrom.

8. The process hereinbefore described, consisting in casting a layout of type slugs, each with a distinctive type character thereon, the several characters being differently positioned on the faces of their respective slugs according to the measurement of the characters, and the slugs being a size to be locked together without intervening spaces or space quads; and arranging and locking 125

together the slugs to form the assembled layout; and making a matrix plate from the slugs so assembled.

9. The process of making matrix plates such as described, comprising the setting of a mold to cast slugs having bodies greater than normal type bodies so that an assembly of such slugs may occupy the space ordinarily occupied by the character type and by the spacing pieces or quads, then approximately positioning a character matrix over the mold and casting a slug having the selected character thereon, then measuring the position of the character on the face of the slug, then adjusting the position of the character matrix over the mold to correct any error in the position of the character on the slug as indicated by the measurement, then casting another slug, so that on the slug last obtained the character is in a precise and predetermined position with respect to two edges of the slug.

10. The process of making matrix plates such as described, comprising the setting of a mold to cast uniform slugs having bodies greater than normal type bodies, so that an assembly of such slugs may occupy the space ordinarily occupied by the type characters and by the spacing pieces or quads, then approximately positioning a character matrix over the mold and casting a slug having the selected character thereon, then measuring the position of the character on the face of the slug, then adjusting the position of the character matrix over the mold to correct the error in the position of the character on the slug as indicated by the measurement, then casting another slug so that on the slug last obtained the character is in a precise and predetermined position with respect to two edges of the slug, then repeating the operation until a complete set of the character slugs is obtained, then assembling the slugs and making the master matrix plate from the slugs so assembled.

11. The process of making a matrix plate in which the matrices will be uniformly distributed in vertical and horizontal lines, which consists in adjusting a character matrix over a rectangular mold of desired size, so as to cause the character face to occupy a desired relation to two sides of the mold, casting a slug in the mold thus formed and

repeating this operation for the entire font, assembling all of the slugs thus formed, 55 without intervening spaces, but with the addition of a sufficient number of blank slugs of the same size into a form, and making a reproduction therefrom.

12. The process of making a matrix plate 60 in which the matrices will be uniformly distributed in vertical and horizontal lines, which consists in forming a series of type slugs for the entire font, having square or rectangular bodies of uniform size, with the 65 characters located upon one end of such bodies each in a predetermined position with respect to two sides of the body, then assembling these slugs into a square and making an electroplate therefrom.

13. The process of making a matrix plate 70 in which the matrices will be uniformly distributed in vertical and horizontal lines, which consists in making a layout of desired size from any font of type, spacing 75 the characters therein uniformly apart in two directions with approximate accuracy, making an electroplate therefrom, mounting the electroplate thus formed upon a pin plate, mounting the combined pin plate 80 and matrix plate in a casting machine, centering by means of the pin plate each matrix over a mold, casting from each matrix type slugs of uniform size, measuring each type slug thus cast to determine the error of 85 placement of the character upon the end of the body, re-adjusting the matrix plate in relation to the mold so as to correct this error, and repeating this action until a full set of perfect type slugs are formed in each 90 of which the character face will be accurately located in relation to two sides of the slug body, then assembling the type slugs thus made in a form, and making therefrom a matrix plate, which may be then attached 95 to any pin plate of standard construction, or be used as a master matrix plate from which stereotypes may be taken for the production of other accurate matrix plates.

Signed by me at New York city, this 20 100 day of February 1908.

WILLIAM NICHOLAS.
